UNITED STATES PATENT OFFICE.

JOHN WESLEY HOWLAND, OF LINCOLN, NEBRASKA.

WIRE-SPLICING RING.

SPECIFICATION forming part of Letters Patent No. 626,702, dated June 13, 1899.

Application filed June 28, 1898. Serial No. 684,661. (No model.)

To all whom it may concern:

Be it known that I, JOHN WESLEY HOWLAND, a citizen of the United States, residing at Lincoln, in the county of Lancaster and State of Nebraska, have invented certain new and useful Improvements in Wire-Fence Tools; and I do declare the following to be a full, clear, and exact description of the invention, such as will enable others skilled in the art to which it appertains to make and use the same.

My invention has relation to wire-fence tools; and the object is to provide a wire-fence tool particularly adapted for splicing broken wires.

With this object in view the invention consists in certain features of construction and combination of parts which will be hereinafter fully set forth.

Figure 1 is a perspective view showing two strands of wire in the act of being spliced by my improved device. Fig. 2 is a similar view of the splicing-ring.

1 denotes the splicing-ring having laterally-projecting arms 2, a stud 3, and a downwardly-projecting hook 4.

In splicing the ends of the wire a loop is first formed in the free end of one of the wire sections and placed around the ring under the stud and above the arms. The free end of the other section is now drawn through the ring and the tongue of a suitable tool, such as shown in my companion application, filed

December 20, 1898, Serial No. 699,808, engaged with its free end. Now by twisting 35 the tool to the left both sections of the wire will be drawn taut, and a further twisting will cause the tool to engage the hook of the ring and throw the said hook upward, thus allowing the loop to slide off the ring and be firmly 40 held by the kink formed in the end of the other section. The free end of the other section is now drawn through the slot 18 of the ring and twisted around the wire, thus securely holding the same taut, while the ring 45 is thus entirely free from the wire.

Changes in the form, proportion, and the minor details of construction may be resorted to without departing from the principle or sacrificing any of the advantages of this invention.

What I claim is—

A splice-ring for the purpose described consisting of the open circular portion having arms projecting laterally from its under edge, 55 and a lug projecting laterally from its body portion above said arms, said ring formed with a downwardly-depending hook, substantially as set forth.

In testimony whereof I have hereunto set 60 my hand in presence of two subscribing witnesses.

JOHN WESLEY HOWLAND.
